DISK HARROW

Samuel Johnston Miller, Corpus Christi, Tex.

Application January 20, 1942, Serial No. 427,398
In Canada December 5, 1940

10 Claims. (Cl. 55—73)

This invention relates to improvements in disk harrows and is particularly directed to the construction of a disk harrow which has superior advantages in simplicity of construction, and durability and general efficiency in operation.

A problem in the operation of disk harrows is that it is difficult to design the disk unit so that it may be drawn by a tractor or horses in a straight line, regardless of the contour of the land and soil conditions.

A further difficulty is that disk harrow units, in operation, have a heavy side thrust which places a constant strain on the frame or frames which carry the disk units.

In my United States Patent No. 2,191,537, issued February 27th, 1940, I disclosed a multiple unit disk harrow wherein a number of disk units are hingedly attached to the main frame in such a manner that each unit is held firmly in fixed position insofar as horizontal and vertical angularity, tillage depth, and side-sway are concerned.

Through the hinged connection of each disk unit to the main frame, each unit is free to rise over any obstruction, such as rocks, independently of the other units, relieving the full weight of the harrow from the contacted disk, thereby avoiding the possibility of damage to the disks, and alignment of the frame.

One of the principal objects of the present invention is to provide an arrangement of parts in a disk harrow which transmits the heavy side thrust of the disk units to the disk wheels which support the frames carrying the disk units. In the preferred embodiment of my invention hereinafter described, this is accomplished by providing the harrow with disk wheels, preferably either two or three in number, at least one of which is located on one side of the harrow and the other on the opposite side. The disk wheels are mounted on a frame which is connected to the frame carrying the disk units in such a manner that the side thrust of the disk units under operating conditions is transmitted to the disk wheels, thereby counteracting the ordinary side thrust found in ordinary disk harrows.

A feature of the present invention resides in the construction and interconnection of the frames which carry the disk wheels and disk units so that each frame and each disk unit is movable in a vertical plane independently of the other frames and the other disk units and, at the same time, the side thrust of the disk units is transmitted to the disk wheels previously mentioned. One advantage of such a construction is that when an obstruction is encountered, for example,

by the disk units, only the disk units encountering the obstruction are raised in passing over it, and subjected to the strain caused by this movement. Likewise, when one of the disk wheels, which absorb the thrust of the disk units, encounters an obstruction, only the wheel encountering the obstruction is raised and no strain is transmitted to the remainder of the machine.

A further feature of the present invention is that the front wheel, or front wheels, is mounted so that it is free to be turned in a horizontal plane, which form of mounting overcomes the difficulty heretofore encountered when the front wheel was not free to turn. In such machines, it was necessary that the tractor, or other form of motive power, had to be located at a fixed point in relation to the line of draft, whereas by using the above-mentioned steering arrangement, that is, with the front wheel, or wheels, free to turn in a horizontal plane, a particular location of the draft means relative to the line of draft is not required.

Other and further features of my invention will be apparent from the following description and the accompanying drawings, in which—

Figure 1 is a top plan view of a disk harrow constructed in accordance with my invention;

Figure 2 is a fragmentary view, partly in perspective, of the front transverse member shown in Figure 1;

Figure 3 is a top plan view of the frame of the disk harrow with the disk units removed;

Figure 4 is a side elevation of Figure 3;

Figure 5 is a detail view of one of the front wheels showing the manner in which it is mounted on the front transverse member;

Figure 6 is a detail view showing the mounting of the disk gang units;

Figure 7 is a front elevation of one of the disk gang units.

Like reference characters refer to like parts throughout the specification and drawings.

The disk harrow illustrated in the drawings includes a main frame, a second frame which is pivotally connected to the main frame to permit movement in a vertical plane of the disk units which are carried by the second frame, and a third frame which is pivotally connected to the main frame and to the disk unit frame. The third mentioned frame extends to the rear of the disk unit frame and is supported on a disk wheel.

In the modification of my invention illustrated in Figures 1 through 7, the main frame comprises a transverse member 10 which is supported by a pair of disk wheels 11—12. Each

wheel 11—12 is rotatably mounted on an axle which is journalled in a channel iron 13. Each channel iron 13 is provided at its upper and lower ends with L-shaped brackets 14—15 respectively. The bracket 14 is pivotally secured to the member 10 by means of bolt 16, and the bracket 15 is pivotally connected to the lower end of brace 17 by means of bolt 18. The upper end of brace 17 is securely attached to the underside of the member 10. A steering arm 19 is securely attached to each channel iron 13. One end of the draw bar 20 is pivotally connected to the member 10. The steering arms 19 are connected to the draw bar 20 by means of the links 21. It will thus be seen that the wheels may be steered by means of the draw bar 20 to follow the direction taken by the tractor.

The transverse bar 10 is braced by means of two bars 22—23 which extend diagonally forwardly from the member 10. Each of the bars 22—23 have one end connected to the member 10 by means of plates 24—25, respectively. The plates 24—25 are located at and secured to the member 10 adjacent the wheels 11—12, respectively. The forward ends of the bars 22—23 are connected together by a cross bar 26.

The frames carrying the disk units include the rearwardly extending spaced apart members 27—28—29—30. The forward end of each of these members is hingedly secured to the member 10. The members 27—28—29—30 are connected together towards their rearward ends by means of the cross bar 31. The ends of the members 27—28 extend rearwardly beyond the cross bar 31 and are connected together by the cross bar 32, one end of which is joined to the cross bar 31. The ends of the members 29—30 extend rearwardly beyond the cross bar 31 and are connected together by a cross bar 33. The two platforms formed by this construction, one at the rear of bars 27—28 and the other at the rear of bars 29—30, may be utilized for carrying weights to adjust the depth to which the disk units penetrate into the soil.

A brace rod 34 extends diagonally beneath the frame carrying the disk units and has one end connected to the frame member 27 at or near the point where the cross member is attached to that frame member. The other end of the brace rod 34 is connected to the brace 17 which supports the channel iron 13, to which wheel 11 is attached.

The tail frame comprises a rearwardly extending member 35 which has one end pivotally connected to the member 10 at or near the pivot point of the member 29 and is bent to pass over the disk unit frame so as to avoid interference with the vertical movement of that frame.

The frame member 35 extends beyond the rear end of the members 29—30 and is connected to the cross member 32 adjacent to the frame member 27 by means of bolts 37 which allow the frame member to move vertically on its pivot.

Brace rod 36 has one end pivotally connected to the member 32 adjacent to the frame member 27 and the other end is connected to the channel member 44, at a point where axle of wheel 45 contacts channel member 44. The brace rods 34—36 act together to transmit the side thrust of the disk units 47—48 to the disk wheels 11—12—45.

The cross frame member 38 extends diagonally across the disk harrow and has one end slidably connected to the frame member 35 at a point immediately above member 33. The other end of

the frame member 38 is pivotally connected to the transverse member 10 by means of bar 39.

The channel member 40 and a frame member 41, parallel to and spaced therefrom, extend rearwardly of the frame members 35. The frame member 41 is connected to the bar 36 and the channel member 40 is connected to the frame member 35. The members 40—41 are interconnected by means of cross members 42—43. Attached to and extending downwardly from the frame member 40 is a channel bar 44 to which is attached a disk wheel 45. The platform formed by the frame members 40—41 and cross members 42—43 can be loaded, such as by heavy stones, to cause the penetration of the wheel 45 to the required depth into the soil.

The disk harrow illustrated in Figures 1 through 7 of the drawings is provided with two disk units 47—48, each of which is preferably constructed in the manner illustrated in Figure 7. Referring to Figure 7, each disk unit includes a plurality of disk blades 49 which are carried on a shaft rotating in bearings 50. The bearings 50 are carried by the bars 52, the upper ends of which are connected to the beam 51. The beam 51 is provided at one end with a bar 53 which extends outwardly and downwardly to a point in line with the center of the end disk blade. The lower end of the bar 53 is provided with a member 54 which passes through a hole in the centre of the end disk blade to engage against a thrust bearing located between the two end disk blades.

Each of the disk units 47—48 is provided with a pivot 55 and is pivotally attached to the frame member 31 in such a manner that the disk units may be turned angularly to the line of draft. The disk unit 47 is pivoted to the frame members 31 and 27 at the point where those members are joined together, and the disk unit 48 is pivoted to the frame members 29—31, where those members are joined together.

The disk harrow is also provided with an arrangement for adjusting the angle of each disk unit with respect to the line of draft. The angle of the disk unit 47 is adjusted by means of a lever 56 which is mounted on the frame member 28 in front of the disk. The lever 56 is connected to the disk unit 47 by means of a connecting rod 57. The disk unit 48 is adjusted by a similar arrangement which includes a lever 58 mounted on the frame member 30 in front of the disk unit 48. The lever 58 is connected to the disk 48 by a connecting rod 59.

It is found in operation that the unit 47 on the right side of the frame tends to sink too deeply into the soil and, therefore, provision is made to maintain this unit at a predetermined depth in the soil. The arrangement of parts by means of which this is effected includes a lever 60 having a chain 61, one end of which is connected to an arm of the lever and the other end is connected to the disk unit. The lever 60 is mounted on the frame member 38, preferably near the pivot 55 of the disk unit 47.

The side thrust of the disk harrow is taken up through the member 54 and transmitted through the member 53 to the beam 51. Thence from the beam 51, the thrust is transmitted through the pivot 55 to the cross member 31 to the bar 36 and to the channel member 44. The last member, channel member 44, distributes through members 34—36 the side thrust evenly to the disk wheels 11—12—45.

It has been found that the hinged construction

of the frames permits the vertical movement of each disk unit independently of the remainder of the units, thereby making it possible for a unit to pass over an obstruction without interfering with the operation of the remainder of the units.

Furthermore, the present construction transmits the thrust to the disk wheels thereby permitting the disk harrow to be drawn in a straight line independently of the contour of the land, the soil conditions, or the point of depth. The steering arrangement, of course, permits flexibility in changing direction which ordinarily is not present in disk harrows which, due to the tendency of swinging sideways on encountering obstructions or difficult soil conditions, must be held in fixed relationship with the motive power.

It will be clearly understood, of course, that modifications may be made to the specific embodiment of the invention described and illustrated herein without departing from the scope of the invention as defined in the appended claims.

I claim:

1. A disk harrow comprising a main frame, a second frame extending to the rear of said main frame and hingedly attached thereto for movement in a vertical plane independently of said main frame, disk units pivoted, on vertical axes, to the second frame, disk wheels supporting said main frame, and means for transmitting the side thrust of said disk units to said disk wheels.

2. A disk harrow comprising a main frame which includes a front axle, a second frame extending to the rear of said main frame and connected thereto for movement in a vertical plane independently of said main frame, a disk unit attached to said second frame, said disk unit being adjustable in a horizontal plane, disk wheels on the axle and second frame for supporting said frames, and means for transmitting the side thrust of said disk units to said disk wheels.

3. A disk harrow comprising a main frame, at least one wheel supporting said frame, and a second frame hingedly attached to said main frame for movement in a vertical plane independently of said main frame, disk units mounted to pivot on the second frame, means cooperating with said supporting wheel for transmitting the side thrust of said disk units to said supporting wheel, said second frame extending to the rear of said main frame, and a disk wheel supporting said second frame, and positioned to the rear of said disk units.

4. A disk harrow comprising a main frame, wheels supporting said frame, a second frame hingedly connected to the main frame for vertical movement, disk units mounted to pivot on vertical axes on the second frame, means cooperating with said supporting wheels for transmitting the side thrust of said disk units to said supporting wheels, said second frame extending to the rear of said main frame, and a disk wheel supporting said second frame, and positioned to the rear of said disk units.

5. A disk harrow comprising a main frame, a disk gang frame hingedly attached to said main frame for movement in a vertical plane independently of said main frame, disk units carried by said disk frame, disk wheels supporting said main frame, and means cooperating with said wheels for transmitting the side thrust of said disk units to said disk wheels, and a tail frame

hingedly attached to said main frame and to said disk gang frame for movement in a vertical plane independently of the aforesaid frame, said tail frame extending to the rear of said main frame and a disk wheel supporting said tail frame and positioned to the rear of said disk units.

6. A disk harrow comprising a main frame, disk wheels supporting said main frame, a second frame hinged to the main frame, disk units pivoted to the second frame means cooperating with said supporting disk wheels to transmit the side thrust of said disk units to said supporting disk wheels, and means for steering said supporting disk wheels, said second frame extending to the rear of said main frame, and a disk wheel supporting said second frame and positioned to the rear of said disk units.

7. A disk harrow having in combination a transverse member, a draw bar connected to said member, wheels supporting said member, and means for steering said wheels including a connecting rod extending from said draw bar to each of said wheels whereby turning movement in a horizontal plane is imparted to said wheels, a disk frame hingedly attached to said transverse member for movement in a vertical plane independently of said transverse member, a second frame extending to the rear of said disk frame, and hingedly attached to said first mentioned frame and to said transverse member for movement in a vertical plane independently of said transverse member and said frame, and a disk wheel supporting the rear end of said second frame.

8. A disk harrow comprising a main frame, a disk gang frame connected to the main frame for movement in a vertical plane independently of the main frame, disk units pivoted on vertical axes on the disk gang frame, disk wheels supporting the main frame, means cooperating with said wheels for transmitting the side thrust of the disk units to the disk wheels, a tail frame connected to the harrow structure for movement in a vertical plane independently of the aforesaid frames, said tail frame extending to the rear of said disk gang frame and a disk wheel supporting said tail frame and positioned to the rear of the disk units.

9. A disk harrow having in combination a transverse member, a drawbar connected to said member, wheels supporting said member, means for steering said wheels including a connecting rod extending from the drawbar and connected to each of said wheels whereby turning movement in a horizontal plane is imparted to said wheels, a disk frame connected to said transverse member for vertical movement relative thereto, a second frame extending to the rear of the disk frame and connected to the disk frame and to the transverse member for vertical movement and a disk wheel supporting the rear end of said second frame.

10. A disk harrow comprising a main frame, wheels supporting said frame, a second frame pivoted for vertical movement at its forward end, to the main frame, disk units pivoted on vertical axes to the second frame, a tail frame pivoted, for vertical movement, to the main frame and second frame, a wheel supporting the tail frame and thrust means connecting the second frame to the tail frame supporting wheel and one of the main frame supporting wheels.

SAMUEL JOHNSTON MILLER.
